PUMPING UNIT FOR BLOOD DURING HEART SURGERY

Samuel I. Lerman, 4205 Fullerton Ave., Detroit, Mich.

Filed Sept. 21, 1960, Ser. No. 62,220

Term of patent 7 years

(Cl. D83—1)

FIG. 1

FIG. 4

FIG. 2

FIG. 3

FIG. 1 is a top plan view of a pumping unit for blood during heart surgery embodying my new design;

FIG. 2 is a front elevational view thereof;

FIG. 3 is a right side elevational view thereof; and

FIG. 4 is a rear perspective view thereof taken from the side opposite that shown in FIG. 3.

I claim:

The ornamental design for a pumping unit for blood during heart surgery, as shown.
